UNITED STATES PATENT OFFICE

2,572,538

AUTOWASHING MAT

Tinie R. Teters, Fayette, Mo.

Application October 14, 1949, Serial No. 121,428

2 Claims. (Cl. 299—83)

1.

This invention relates to an automobile washing mat of novel design, particularly and efficiently adapted for the washing, with ease and facility, of all exterior parts of automobiles, buses, trailers, streetcars, and the like.

An important object of the present invention is to provide a device of the type stated which will permit the washing of a vehicle with a minimum of time and effort.

Another important object is to provide a device as described wherein clear water, soap-treated water, or other cleansing liquids can be applied separately or in unison, depending upon the needs of the particular task.

Still another important object is to provide a construction for such a device wherein clear and soap-treated water can be supplied separately to the device and will be blended within the device before being fed to the surface to be washed.

Another important object is to provide a device as described which will be adjustable as to its handle, with said handle being adapted additionally to be detached entirely, whereby the washing mat can be readily and conveniently used for washing tires, inaccessible or distant parts of the vehicle, etc.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Fig. 1 is a perspective view of an auto washing mat constructed in accordance with the invention.

Fig. 2 is a bottom plan view of the mat portion thereof.

Fig. 3 is an enlarged transverse section through said mat portion.

Fig. 4 is a top perspective view of a water bag embodied in the device.

Fig. 5 is a bottom perspective view of said water bag.

Fig. 6 is a reduced top plan view of the washing pad of the device.

Referring to the drawings in detail, I provide an elongated tubular handle 5, and telescoping in one end thereof is the extensible grip 6 adapted to be secured in selected positions of adjustment relative to the tubular handle by means of the thumb screw 7. The inner end of the elongated tubular handle 5 is split, and the split

2.

portions are outturned to provide ears 8 secured by rivets 9 to one end of a yoke 10, the arms of which have inturned free ends 11 removably and pivotally positioned within the ends of a tube 12, 5 formed at its ends with feet 13 riveted at 14 to diametrically opposite portions of a disc 15 of metal, plastic, or other suitable material.

Secured by rivets 16 to the metal disc 15 is the circular plate 17 having the depending marginal flange 18.

Referring now to Figs. 4 and 5, I provide a water bag that is positioned in the recessed underside of the plate 17, the water bag including an upper canvas facing 19, the marginal edge 20 15 of which is secured by stitching or similar means to the marginal edge of a lower canvas facing 21, and filling the spaces between the facings 19 and 21 is sponge material 22.

For the purpose of feeding clear and soap-treated water to the interior of the water bag, I provide the spaced hose fittings 23 mounted in the central part of the upper canvas facing 19 and communicating with the interior of the water bag. The hose fittings 23 extend upwardly through openings 24 formed in the plate 17 and are adapted to have removably connected thereto hoses 25. One hose 25 can lead from a hydrant or tank of clear water, and said clear water can be fed to the interior of the water bag either by gravity or by hydrant pressure as desired. The other hose 25 can extend from a tank containing soap-treated water or the like, with said tank being disposed at an elevated position so as to feed the soap-treated water by gravity to the interior of the water bag. When the clear and soap-treated water arrives within the water bag, they are blended therewith before being discharged through the bottom of the water bag through a plurality of spaced grommets 26 defining discharge openings in the bottom of said bag.

The blended water is fed thereafter to a cleansing pad comprising the wool bottom portion 27 that constitutes the contact surface with the vehicle to be washed. The wool portion 27 is securely fastened either adhesively or naturally to the leather backing 28, to the marginal portion of which is secured the annular canvas collar 29, the outer periphery of which is upwardly extended as at 30, and secured either adhesively 45 or by other suitable means to the marginal portion of an elastic annular member 31, adapted to overlie the marginal part of the plate 17 and grip said plate for the purpose of holding the cleansing pad securely to the plate in position 50 under the water bag.

I believe the assembly and operation of an au-

tomobile washing pad formed in accordance with the invention can be readily noted at this time. The entire handle portion, as will be readily observed, can be removed entirely so that the washing mat can be applied directly to such automobile parts as the wheels, tires, etc. When using the device with the handle portion removed, the tube 12 itself comprises the handle that is readily gripped by the user.

If the handle member is to be used for reaching parts of the vehicle that are not as accessible as those described immediately above, it is necessary only that the arms 10 of the handle yoke be resiliently spread apart so as to permit the inturned ends 11 thereof to enter the opposite ends of the tube 12. By this means the entire handle portion of the device is pivotally attached to the washing head thereof.

Considering the operation of the head or mat portion itself, hoses 25 are attached to the hose fittings or nipples 23, and clear and treated water can be supplied to the water bag either separately or together. Within the water bag, the different liquids applied thereto are blended and this blending action is aided by the fact that in the meantime the user will be pressing downwardly upon the surface to be washed, thus alternately squeezing and expanding the sponge 22 contained within the water bag. In any event the blended water is then fed in the direction of the arrows shown in Fig. 3, through the grommets 26, after which the blended water is forced through openings 32 formed in the surface of the leather backing 28 of the pad 27. The blended water is thus dispersed evenly and uniformly through the wool cleansing member 27 and thus is applied to the surface of the vehicle while the user is at the same time applying normal, light rubbing action of the washing pad across the vehicle surface.

What is claimed is:

1. In a washing device a top plate including a peripheral depending flange defining a recess in the underside of the plate; a water bag proportioned to fill said recess completely, the water bag

including inlet fittings projecting through and engaged by said plate to retain the water bag within the recess, a bottom face having a plurality of outlet openings, said bottom face being formed from flexible material, said bottom face being flexible toward the plate in the central area of the water bag and constituting means for compressing the water bag at said central area, said flange preventing compression of the water bag in the marginal area thereof, and sponge material completely filling said water bag.

2. In a washing device a flat plate including a narrow depending peripheral flange, said flange defining a shallow recess under the plate; and a water bag completely filling said recess and proportioned to a thickness approximately equal to the width of said flange, said water bag including a flexible top face lining the walls of said recess, inlet fittings secured to said top face and engaged in said openings of the plate to retain the water bag within the recess, a flexible bottom face having a plurality of outlet openings secured at its periphery to the periphery of the top face, said bottom face being flexible in the direction of the top face in the central area of the water bag for compression of the water bag in said central area, said flange of the plate rigidifying the periphery of the water bag to prevent compression of the water bag in the peripheral area thereof, and sponge material completely filling the space between the top and bottom faces of said water bag.
